UNITED STATES PATENT OFFICE.

RICHARD WEBB BURNETT, OF MONTREAL, QUEBEC, CANADA.

ROOF.

1,170,219.

Specification of Letters Patent.

Patented Feb. 1, 1916.

Application filed March 25, 1912. Serial No. 686,105.

To all whom it may concern:

Be it known that I, RICHARD WEBB BURNETT, of the city of Montreal, Province of Quebec, Dominion of Canada, have invented 5 certain new and useful Improvements in Roofs; and I do hereby declare that the following is a full, clear, and exact description thereof.

My invention relates to all metal car roofs 10 and it has for its object to provide a roof of this type affording facility for ventilation and less liability to buckle and bulge when walked upon.

To this end the invention may be said 15 briefly to consist of a roof comprising roof sheets with upwardly offset overlapping edges inclosed by carlines of inverted U cross-section, the edges of the sheets being either self-sustaining or supported by 20 bridges secured to the interior of the legs of the carline by means clamping the overlapping portions to the bridges.

Other elements of the invention consist in 25 structural features by which the carlines tightly inclose the portions of the sheets contiguous to their edges and thus eliminate vertical play between the sheets and carlines, and the side plates and ends of the carlines are conjointly formed to afford effective 30 ventilating means without danger of cinders and dust entering, while the ends of the sheets extend down over the side-plates and are stiffened in order to prevent them from springing out from the side plates between the carlines.

For full comprehension, however, of the 35 invention reference must be had to the accompanying drawings forming a part of this specification in which similar reference 40 characters indicate the same part, and wherein:

Figure 1 is a side elevation of a portion of a roof containing my invention; Fig. 2 is a transverse sectional view taken on line A A 45 Fig. 1; Fig. 3 is a similar view to Fig. 2 with the carline roof-sheet and side plate slightly separated to illustrate the relative configuration of the carlines and sheets; Fig. 4 is a vertical sectional view transversely to the 50 carline on line B B and drawn to an enlarged scale; Fig. 5 is a vertical sectional view on line C C Fig. 4 with the clamping means in elevation; and Figs. 6 and 7 are similar views to Figs. 4 and 5 of a modification.

The roof-sheets are indicated at *b*, the car-

lines at *c*, and the side plates at *d*, the side plates being bolted to the side timbers *e* of the car in any way preferred by the car builder and therefore not shown. The roof-sheets have their side edges upwardly offset and correspondingly curved as at *f* and overlapped within the carlines which are of flanged inverted U-form in cross-section, the flanges being indicated at *g*. The side 60 plates are of Z cross-section and the ends of the roof-sheets are bent down over them, the corners being sheared off as at *h* to clear rivets *i* by which the ends of the flanges of the carlines are fastened to the side plates. 70

The carlines and roof-sheets are upwardly curved as shown in Fig. 2 and in order to increase the reinforcing qualities of the carlines relatively to the sheets the curve of the former is at a slightly wider radius than 75 the carlines. The effect is that the sheets being laid in place first when the carlines are lowered over them the portions of the sheets contiguous to the upwardly offset edges are more or less crowded into the concavity of the carline flanges and when the 80 ends of the latter are riveted to the side plates there is absolutely no vertical play between the sheets and carlines. This is important in preventing depression of the 85 roof-sheets when walked upon at one side of the middle, the depression being impossible without upwardly bulging on the other side of the middle which the lack of play and snug fit and rigidity of the carlines 90 prevent. This feature is clearly illustrated by Figs. 2 and 3.

Ventilation is afforded by apertures in the ends of the carlines, and cinders, dust and snow are prevented from being blown 95 into the apertures by providing openings *j* in the outside horizontal flanges *k* of the side plates in position registering with the interior of the carlines. These apertures are formed by cutting away the head and 100 legs of the U of the carlines as at *v*, the flanges thereof extending down to and resting at their ends upon the flanges *k* as shown in Figs. 1 and 2.

When using light-weight roof-sheets I 105 prefer to support the upwardly offset edges thereof by bridging straps *m* riveted to the legs of the carlines as at *n* and having the overlapping edges of the sheets clamped thereto by bolts *o* extending downwardly 110 through the straps and sheet-edges and through convex bars *p* with flat undersides,

such bars being brought and held in clamping relation with the bridging straps by tapered split keys *s* driven into a slot *t* in the bolt.

5. In order to prevent ingress of cinders, dust and snow between the turned down ends of the sheets between the carlines and the side plates the sheets are formed with a bead *u* adjacent and parallel to the edge. The bead 10 stiffens the edge of the sheet and prevents it from springing away from the side plate even if not otherwise held. The sheets are preferably corrugated at wide intervals.

What I claim is as follows:—

15. 1. In a car roof, the combination with carlines of inverted U-form, of roof-sheets having overlapping upwardly offset side edges enveloped by the carlines.

20. 2. In a car roof, the combination with carlines of inverted U-form, of roof-sheets having overlapping upwardly offset side edges enveloped by the carlines and means fastening the said edges of the sheets within the carlines.

25. 3. In a car roof, the combination with carlines of inverted U-form, of roof-sheets having overlapping upwardly offset side edges enveloped by the carlines, bridging straps riveted at their ends to the interior 30 of the legs of the carline, clamping bars beneath the overlapping edges and bolts extending downwardly through the straps, sheet edges and bars, and clamping devices carried by the protruding ends of the bolts.

35. 4. In a car roof, the combination with carlines of inverted U-form, of roof-sheets having overlapping upwardly offset correspondingly curved side edges enveloped by the carlines.

40. 5. In a car roof, the combination with carlines of inverted U-form, of roof-sheets having overlapping upwardly offset correspondingly curved side edges enveloped by the carlines, bridging straps riveted at their 45 ends to the interior of the legs of the carline, clamping bars beneath the overlapping edges and bolts extending downwardly through the straps, sheet edges and bars, and clamping devices carried by the protruding ends of the bolts.

50. 6. In a car roof the combination with side plates of reversed-Z cross-section, and a carline of inverted U-cross-section with its ends turned down and supported upon the outside horizontal flange of the side plate and having a ventilating aperture therein.

55. 7. In a car roof the combination with side plates of reversed-Z cross-section and a carline of inverted U-cross-section with its ends turned down and supported upon the outside horizontal flange of the side plate and having a portion of its lower edge disposed in an oblique plane.

60. 8. In a car roof the combination with side plates of reversed-Z cross-section, and a car-

line of inverted U-cross-section with its ends turned down and supported upon the outside horizontal flange of the side plate and the said horizontal flange having an opening communicating with the interior of the 70 carline.

9. In a car roof the combination with side plates of reversed-Z cross-section, and a carline of inverted U-cross-section with its ends turned down and supported upon the outside horizontal flange of the side plate and having a ventilating aperture therein, the said horizontal flange having an opening 75 communicating with the interior of the carline.

10. In a car roof the combination with side plates of reversed-Z cross-section, and a carline of inverted U-cross-section with its ends turned down and supported upon the outside horizontal flange of the side plate 35 and having a portion of its lower edge disposed in an oblique plane the said horizontal flange having an opening communicating with the interior of the carline.

11. In an all metal car roof, an upwardly 90 curved carline, and an upwardly curved roof sheet, the radius of curvature of the carline being greater than that of the roof sheet.

12. In a car roof, the combination with 95 relatively movable load-sustaining roofing sheets having flanged edges, of a carline extending over and weather-proofing the flanged edges of said sheets, and means suspended from said carline and located above 100 the plane of the sheets for supporting the same and permitting the relative movement.

13. In a car roof, the combination with side plates of relatively-movable load-sustaining roofing sheets extending across between said side plates and having flanged adjacent edges, a load-sustaining carline secured to said plates intermediate said sheets extending over and weather-proofing the flanged edges thereof, and means suspended 110 from said carline for supporting said sheet intermediate said plates, said means being located above the plane of the sheets.

14. In a car roof, the combination with side plates, of a carline extending across between said side plates and secured thereto, relatively movable load-sustaining roofing sheets arranged upon opposite sides of said carline and having flanged edges extending beneath said carline and weather-proofed thereby, and means suspended from said carline for supporting said sheets intermediate said side plates, said means being located above the plane of the sheets.

15. In an all metal car roof, an upwardly 125 curved carline, and an upwardly curved roof sheet, the radius of curvature of one being greater than that of the other.

16. In a car roof, the combination with carlines of inverted U-form, of flanged over- 130

lapping roof sheets having flanges at adjacent edges enveloped by the carlines, and means for supporting said roof sheets positioned wholly above the plane of the unflanged portion of said roof sheets.

17. In a car roof, the combination with carlines of inverted U-form, of roof sheets having offset overlapping side edges enveloped by the carlines, and means for supporting said roof sheets engaging the offset

portion of said roof sheets above the plane of the main portion of said roof sheets.

In testimony whereof I have signed my name to this specification in the presence of two witnesses.

RICHARD WEBB BURNETT.
